UNITED STATES PATENT OFFICE.

MICHAEL GATES, OF DECATUR, MICHIGAN.

HORSESHOE.

SPECIFICATION forming part of Letters Patent No. 405,470, dated June 18, 1889.

Application filed October 23, 1888. Serial No. 288,974. (No model.)

To all whom it may concern:

Be it known that I, MICHAEL GATES, a citizen of the United States, residing at Decatur, in the county of Van Buren and State of Michigan, have invented certain new and useful Improvements in Soft-Ground Horseshoes, of which the following is a specification, reference being had therein to the accompanying drawings, in which—

10 Figure 1 represents a perspective view of my improved soft-ground shoe complete; Fig. 2, a transverse sectional view thereof; Fig. 3, a detail sectional view of one of the eccentric buttons or cams, and Fig. 4 a detail sectional view of one of the heel clamps or holders.

15 The object of this invention is, essentially, to provide a simple and practical soft-ground or mud shoe that may be readily adjusted and applied to hoofs of various sizes whether 20 the same be smooth or rough-shod, or not shod at all, as will be more fully hereinafter set forth.

25 The invention will be understood from the following description when taken in connection with the annexed drawings; and it consists of certain novel features of construction that will be fully hereinafter described, and pointed out in the claim appended.

30 The letter A designates the shoe proper, which is of the usual shape, and consists of a thin concavo-convex metallic plate having formed around its upper edge a vertical integral flange a, the concave side of the shoe being the under side. The plate or shoe 35 as thus constructed will be less likely than those now in use to collect mud, &c. This shoe will also be less likely to cut the limbs of the horse should he flounder, which is frequently the case. The lower corner or edge 40 of the plate may be beveled or rounded off, as shown most clearly at a' in Fig. 3, to further guard against injuring the animal's limbs.

45 Two adjustable hoof clamps or bails B B are employed to clamp this shoe to the hoof 45 of the animal. These clamps each consist of a curved bar adapted to fit over the front of the hoof and provided with perforated ears b for the passage of a clamping-bolt c, provided with a nut. The lower ends of the bails 50 or clamps are provided with oppositely-projecting lugs d, and are passed through trans-

verse slots e in the shoe A, the slots being upon opposite sides of the shoe. The slots prevent the withdrawal of the clamps while in use, and at the same time permit them to 55 be adjusted to and from each other to fit different-sized hoofs. Bosses or enlargements f are formed on the under side of the shoe around the slots e to form a horizontal bearing-surface for the lugs d and keep the bails 60 at a uniform height.

The plate A is provided with openings for the toe and heel calks of the shoe in case the animal should be rough-shod. Formed on the upper face of the plate directly behind the 65 heel-calk openings are the transverse serrated bosses g. Clamped down upon these serrated bosses are the adjustable heel-clamping blocks C, the forward ends of these blocks being notched to receive the heels of the shoe. 70 When the animal is unshod, the sharpened and pronged forward ends of the blocks C, formed by the V-shaped notches, may be pressed up close to the hoof and assist in clamping the same. It is obvious that the 75 bosses g may be omitted and the transverse serrations formed in the upper surface of the plates; but I prefer the construction shown. The under surfaces of the heel-clamping blocks are also transversely serrated to engage with the serrations of the bosses g. The blocks C are longitudinally slotted for the passage of the clamping-bolts h, which are passed through the plate A and are provided with nuts upon their upper screw-threaded 80 ends. The bolt-passage through the plate A may also be elongated to permit of the further adjustment of the clamping-blocks, as shown in Fig. 4.

Pivoted upon bosses formed on the upper surface of plate A or directly upon the face of the same are the eccentric buttons D, the buttons in this instance being arranged upon opposite sides of the plate, so as to bear against opposite sides of the hoof and assist 90 in holding it in place on the same. These buttons are pivotally secured to the plate by means of the vertical bolts i, which pass through the plate and the button, and are provided on their upper end with tightening-nuts. In adjusting these buttons to a hoof 95 the nuts are loosened and the buttons turned 100

around until their beveled or inclined peripheries bear against and clamp the sides of the hoof or shoe, when the nuts are again tightened to hold the buttons in their adjusted position. Any number of these beveled clamping-buttons may be employed, and they may be placed so as to bear upon any portion of the hoof or shoe of the animal, as is evident.

Having thus fully described my invention, what I claim as new, and desire to secure by Letters Patent, is—

A soft-ground shoe consisting of a plate, adjustable hoof-clamps attached to the plate,

adjustable heel-clamps C C, also attached to the plate, and beveled eccentric buttons D D, pivoted upon opposite sides of the said plate and adapted to bear upon opposite sides of the hoof and assist in clamping the shoe thereto, substantially as described.

In testimony whereof I affix my signature in presence of two witnesses.

MICHAEL GATES.
